ATTACHMENT FOR INFANT'S FOLDING
BATH STAND AND DRESSING TABLECharles T. De Puy, Rochester, N. Y., assignor to
Trimble Nurseryland Furniture, Inc., Rochester,
N. Y., a corporation of New York

Application January 23, 1939, Serial No. 252,340

2 Claims. (Cl. 211—149)

This invention relates to an attachment for an infant's folding bath stand and dressing table, with more particular reference to the type of equipment comprising a cross-legged or camp-stool type of stand arranged to support a tub between the foldable leg frames and combined with a dressing table positionable over the stand and tub or movable to an inoperative position at the rear of the tub, and it has for its object to afford a shelf or tray located when in operative position so as to be conveniently accessible to a mother handling an infant, and foldable in such a way as not to interfere with the usual collapsing or packing of the stand and table.

In a more particular aspect, the invention has for its purpose to afford a light weight and economical arrangement providing a shelf of substantial size, located under the tub between the legs of the inner leg frame in position to support a variety of toilet articles for use during an infant's bath, or when dressing or otherwise taking care of the child.

Another objective of the invention is to afford a shelf which when in operative position does not interfere with or inconvenience the ordinary use of the tub and dressing table, and which presents an attractive and altogether balanced and harmonious appearance in conjunction with the folding stand, tub, and table.

Still a further purpose of the invention is to afford a construction of simple and inexpensive design which holds a shelf securely in either its operative or folded position, and enables one to move the shelf readily from its operative to its inoperative positions, and also to release it quickly when in folded position and permit it to occupy its operative position.

To these and other ends, the invention consists in the construction and arrangement of parts that will appear clearly from the following description when read in conjunction with the accompanying drawings, the novel features being pointed out in the claims following the specification.

45 In the drawings:

Fig. 1 is an end elevation of a conventional type of folding bath stand showing a preferred embodiment of the invention applied thereto, with the shelf in horizontal operative position;

50 Fig. 2 is a front elevation of the same;

Fig. 3 is an end elevation showing the shelf, stand, and table folded;

Fig. 4 is a rear elevation of the same parts in folded relation, and

55 Fig. 5 is an enlarged sectional view on the line

5—5 of Fig. 4, looking in the direction indicated, showing the shelf in its folded or inoperative relation to the leg frame on which it is supported.

Referring more particularly to the drawings in which like reference numerals refer to the same parts throughout the several views, 1 and 2 designate the legs of the inner and outer leg frames respectively, which are pivotally connected at 3 at points intermediate the ends of the legs. The legs 1 and 2 are connected by top rails 4 and 5 respectively and bottom rails 6 and 7 respectively.

The leg frames just described constitute a folding cross-legged or camp-stool type of stand, between the top rails 4 and 5 of which may be supported a tub of rubber or other suitable fabric 8, although the invention to be described more in detail hereinafter may be also applied to a folding stand arranged for supporting a porcelain tub between the leg frames.

9 designates a conventional type of dressing table that is positionable over the tub, as shown in Figs. 1 and 2, or may be swung to an upright inoperative position at the rear of the tub, and to this end the dressing table 9 includes a frame provided with suitable ears or supporting members which are hinged to the rear leg frame 2 at 10 to permit the table to swing to an upright position, while 11 designates a spring connecting the rear of the dressing table with the leg frame and serving to facilitate and assist in the upward movement of the table and to retard its lowering movement. When the stand is folded, the table is swung forwardly to hold the leg frame collapsed, as shown in Fig. 3.

The parts thus far described are known in the art, and one of the objections to structures of this character has been the lack of shelf space to support the toilet articles that are useful and needed during the bathing of an infant, and to accomplish this, there has been provided a shelf or tray located beneath the tub at a height for convenient accessibility and arranged so that it can be folded in alignment with one of the leg frames when not in use so as not to interfere with the collapsing of the stand or to increase its bulk when folded.

The structure referred to preferably comprises a shelf or tray consisting of a bottom 12 and an upstanding ledge or wall 13 around its edges. The shelf is located between the legs of the inner leg frame 1 and is pivotally supported thereon at points near the rear of the shelf by means of suitable screws or pins 14 extending through the upstanding ledge 13 and entering the legs 1. Thus the shelf is arranged to swing about the 55

- pivots 14 from the inoperative folded position illustrated in Figs. 3 to 5 inclusive to the horizontal operative position illustrated in Figs. 1 and 2. It will be observed that when the shelf is in its folded position, it is located substantially in alignment with the legs 1 of the leg frame, and parallel to the plane thereof so that it does not interfere with the collapsing of the stand or dressing table.
- 10 The shelf is supported in its horizontal position by suitable means such as flexible members consisting of tapes or straps 15, one end of each of which is fastened to a leg 1 while the other end is fastened to the shelf at a point near its forward portion so as to retain the latter in horizontal position, as shown in Fig. 1. In order to hold the shelf in its inoperative folded position, there are preferably provided cooperating spring means on the leg frame and shelf such as yieldable spring sockets 16 fastened to the inner surfaces of the legs 1 and arranged to receive spring lugs 17 carried at the side forward portions of the shelf, so that when the latter is swung upwardly, the spring lugs 17 engage the spring sockets 16 and hold the shelf in its inoperative position by frictional engagement between these parts. The shelf can be moved to its operative position by exerting a slight pressure downwardly on its forward edge, sufficient to overcome the spring action of the sockets 16, whereupon the shelf is released and drops to its lowered position where it is supported by the straps 15.
- 15 The shelf is pivoted to the leg frame at a point slightly beneath the pivotal connection between the leg frames so that it is in a position of convenient accessibility but will not strike the tub when elevated. By mounting the shelf on the inner leg frame, the upper portion of which is at the front of the stand, the shelf in moving from its operative to inoperative positions moves through an angle of less than 90°, and when in its inoperative position, is located so that it can easily be engaged beneath the top of the stand and released for use.
- 20 While the invention has been described with reference to a particular embodiment, it is not confined to the details of construction shown and described, and this application is intended to cover such modifications as may come within the

purposes of the improvement or the scope of the following claims.

I claim:

1. The combination with a folding stand including inner and outer legs frames pivotally connected at points intermediate the ends of the legs thereof, the upper part of the inner leg frame constituting the front of the stand, of a shelf pivotally mounted on the legs of the inner leg frame at points which are spaced substantially 10 from the rear edge of the shelf and below the pivotal connections between the leg frames, means at the ends of the shelf cooperating with devices on said legs and acting to hold the shelf in its uppermost position in alignment with said 15 legs, and means connecting the shelf with said legs and acting to limit the downward movement of the shelf and retain it in a horizontal operative position, the upper edge of the shelf being readily accessible when folded into inoperative 20 position and movable downwardly into operative position and the shelf when in operative position extending rearwardly beyond the pivotal point between the leg frames.

2. The combination with a folding stand in- 25 cluding inner and outer leg frames pivotally connected at points intermediate the ends of the legs thereof, the upper part of the inner leg frame constituting the front of the stand, of a shelf comprising a bottom and an upstanding wall 30 around its edges, said upstanding wall being pivotally mounted on the legs of the inner leg frame at points which are spaced substantially from the rear edge of the shelf and below the pivotal connections between the leg frames, separable fas- 35 tening devices on said leg frame and said shelf acting to hold the latter in its uppermost position in alignment with the legs of said leg frame, and flexible tapes connecting the shelf with said legs and acting to limit the downward movement of the shelf and retain it in a horizontal operative position, the upper edge of the shelf being readily accessible when folded into inoperative position and movable downwardly into operative position and the shelf when in operative position extend- 40 ing rearwardly beyond the pivotal point between the leg frames.

CHARLES T. DE PUY.
